CLAIM

The ornamental design for a trigger sprayer shroud, as shown and described.

DESCRIPTION

FIG. 1 is a perspective view of a trigger sprayer shroud showing our new design.

FIG. 2 is a rear view of the trigger sprayer shroud shown in FIG. 1.

FIG. 3 is a perspective view of the trigger sprayer shroud shown in FIG. 1.

FIG. 4 is a front view of the trigger sprayer shroud shown in FIG. 1.

FIG. 5 is a top view of the trigger sprayer shroud shown in FIG. 1.

FIG. 6 is a bottom view of the trigger sprayer shroud shown in FIG. 1.

FIG. 7 is a side view of the trigger sprayer shroud shown in FIG. 1; and,

FIG. 8 is a side view of the trigger sprayer shroud shown in FIG. 1.

The broken lines immediately adjacent to the shaded areas represent the bounds of the claim. All other broken lines depict environmental subject matter. None of the broken lines form a part of the claimed design.
